METHOD OF AND APPARATUS FOR APPLYING CAKE REINFORCEMENTS

Application filed July 27, 1926. Serial No. 125,261.

In a copending application by Arthur Wright and Frank W. Young, Serial No. 115,481, filed June 12, 1926, there is disclosed a reenforcement for deposits, such as filter cake, comprising, in the preferred embodiment, a plurality of separate, endless, substantially flexible members about which the deposit is built up by the migration thereto of solid particles in suspension in a liquid.

10 The present invention relates to reenforcements of the same general character. In the application of the reenforcement in situations say where the members are to be directed about both a rotary deposit forming device and a drying drum or other cylindrical element, considerable difficulty is experienced and much time and labor is involved in laying the strands in proper relative position and closing the respective ends 20 to form a continuous member.

The present invention has for its object the facilitation of the application of a plurality of spaced strands about a rotary deposit forming instrumentality and other cylindrical units associated therewith and the union of their respective ends to form continuous or endless members. Accordingly, a plurality of strands of the desired character are laid upon and secured to a sheet in properly spaced and preferably parallel relation so that the sheet as a whole may be caused to encircle the associated cylindrical elements until the edges are juxtaposed when the respective ends of the strands will meet 30 and may be secured together. Thereafter the sheet may be removed leaving the endless strands in operative position on the machine.

The invention also has to do with the article of manufacture which may be made 40 of indeterminate length and cut to the desired length and dispensed for replacement of worn reenforcing members as occasion requires. In the preferred embodiment, the strands are glued to a sheet of textile or fibrous material, such as heavy paper, and a second sheet say of tissue paper is laid upon the strands for their protection.

The invention also seeks to provide a method of, and an instrumentality for, accomplishing the manufacture of the afore-

said article. Accordingly, a roll of fibrous material, say, is mounted adjacent an adhesive applying device to which a sheet of the material is led from the roll to have the adhesive applied to one side thereof. A plurality of strands are then directed from a plurality of spools and laid upon the treated side in the desired relation, a sheet, say of tissue paper, being then directed, from a roll thereof, to the treated side of the first sheet upon which the strands have been applied.

These and other objects of the invention and the means for their attainment will be more apparent from the following detailed description taken in connection with the accompanying drawings, illustrating preferred embodiments of the invention, in which:

Figure 1 is a view, in side elevation, showing one type of continuous filter and filter cake drying device to which the method of applying a filter cake reenforcement formed of separate continuous members is applicable.

Figure 2 is a plan view showing a fragmentary portion of the article of manufacture including the reenforcing medium comprised of separate spaced strands serving as the vehicle by which the reenforcing medium is applied to a cake or deposit forming instrumentality.

Figure 3 is a somewhat schematic view showing an instrumentality by which the article of manufacture is made.

Figure 4 is a detail view showing a fragmentary portion of the instrumentality illustrated in Figure 3, looking in the direction indicated by the arrows 4-4 in that figure.

The reenforcement A for a deposit such as filter cake comprises a plurality of separate, spaced, parallel and continuous or endless strands, such as are shown at *a* in Figure 2 and which are adapted to be looped, as shown in Figure 1, about a cake forming instrumentality, say the continuous filter *b*, and another cylindrical element such as the drying drum *c* and/or a cake stripping roller *d* and/or guide or idler rollers *e* all as described in the copending application. It will be readily appreciated that were a plurality of independent strands *a* individually looped

about the cylindrical elements as shown and their respective ends tied to form continuous members, considerable time and effort would be required and difficulty experienced in selecting and tying the proper ends together. This procedure is facilitated according to the present invention by applying the strands in the desired relation to a sheet a' of suitable material such as heavy paper and then looping the sheet with the strands applied as a whole about the cylindrical elements until the ends of the sheets are in juxtaposition. It will then be found that the respective ends of each strand are proximate one another and may be tied together without confusion or mistake. To facilitate handling and to protect the strands, a second sheet a^2 of suitable material such as tissue paper is overlaid as shown in Figure 2. After the respective ends are all tied together and a plurality of endless members are formed, the carrier layers of paper a' and a^2 may be readily removed as will be understood.

In Figure 3 there is illustrated an instrumentality by which the article shown in Figure 2 may be made. The sheet of heavy paper a' is formed in a roll at a^{2x} from which it is drawn in the direction indicated by the arrow x through adhesive applying devices by which a suitable adhesive is applied to one side. Upon this treated side of the sheet a' , a plurality of the strands a are held by a comb-like guide g to which they are fed, respectively, from a series of spools or reels h , the strands a being applied to the sheet by adjustable pressure rolls i and in order that the pressure rolls may be protected from the adhesive a second sheet, say of tissue paper a^2 is drawn from the roll a^{2x} and directed through the pressure rolls i as shown, the completed article A coming out of the rolls i and being reeled up into the roll A^x .

It will thus be seen that a method of applying a spaced continuous strand reenforcement to deposit forming devices has been provided in which the strands are carried by a vehicle of sheet form and applied all at once so that the respective ends may be united in a convenient manner without confusion or mistake. A method of and instrumentality for manufacturing the vehicle has also been provided.

Various modifications will occur to those skilled in the art in the form and composition of the vehicle for the reenforcement as well as the uses to which it may be put and in the method of its manufacture as well as in the instrumentality by which it is made and no limitation is intended by the foregoing phraseology or accompanying drawings beyond that set forth in the appended claims.

What is claimed is:

1. As an article of manufacture, a vehicle for the application of spaced filter cake re-enforcing strands to rotary drum filters com-

prising a sheet of heavy paper, a plurality of strands, an adhesive to removably secure the strands to one side of the sheet in predetermined spaced and substantially parallel relation, and a sheet of tissue paper overlying the strands and pasted thereto, and to the heavy paper. 70

2. The method of applying a plurality of spaced strands in encircling relation about a cylindrical element which includes securing the strands in predetermined position upon a sheet, encircling the sheet so formed about the element, causing the ends of the sheet to abut, securing together respective strands and removing the sheet. 75

3. The method of applying a plurality of spaced continuous, flexible strands in predetermined relation about a rotary filter and a cylindrical member which consists in disposing the strands in predetermined relation between sheets of fibrous material with the aid of adhesive, encircling a sheet of predetermined length about the filter and the cylindrical member until the ends abut, securing together the proximate ends of the respective strands and removing the sheets of fibrous material. 80 85 90

4. As an article of manufacture, a vehicle for the application of spaced filter cake re-enforcing strands to rotary drum filters comprising a sheet of fibrous material, a plurality of separate spaced flexible strands and an adhesive to removably secure the strands to the sheet. 95

5. As an article of manufacture, a vehicle 100 for the application of spaced filter cake re-enforcing strands to rotary drum filters comprising a sheet of material, a plurality of separate spaced flexible reenforcing strands, an adhesive to removably secure the strands 105 to the sheet and a second sheet overlying said strands and said first named sheet and removably secured to said strands and to said first sheet.

This specification signed this 21st day of 110 July, A. D. 1926.
